UNITED STATES PATENT OFFICE.

MOSES F. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,300,588.

Specification of Letters Patent. Patented Apr. 15, 1919.

Application filed December 8, 1917. Serial No. 206,331.

To all whom it may concern:

Be it known that I, MOSES F. CARR, a citizen of the United States, and a resident of Newton, in the county of Middlesex, 5 Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to improvements in fasteners, and more particularly, though 15 not exclusively, to improvements in separable fasteners for automobile curtains wherein the stud is adapted to be attached to the curtain and the socket to be carried in a recess in the automobile body, the exterior 20 surface of the socket preferably being substantially flush with the exterior surface of the body.

In the drawings:—

Figure 1 is a front elevation of a preferred form of my invention;

Fig. 2 is a sectional elevation thereof on the line 2—2 of Fig. 1; and

Fig. 3 is a section on the line 3—3 of Fig. 2.

30 In the illustrative embodiment of my invention shown in the drawings, I have provided the stud 4 attached to the curtain 5 of an automobile, and projecting inwardly therefrom for engagement with a socket 6 fastened in the side of the car 7 preferably by screw-threads 8, as shown. The stud 4 is preferably provided with grooves 6' and 7', one of which is preferably adapted to engage with a preferably annular resilient, 35 jaw 9 in the front of the socket 6, and the other of which is adapted to engage with a second resilient jaw element 10 located near the back of the socket. The stud 6 may be attached to the curtain 5 in any suitable 40 way, but I prefer to attach it by the screw-threaded stud 11 passing through the curtain and adapted to engage a knob or button 12 exterior to the curtain. The head 13 of the stud 4 is preferably rounded on the edges so that when the stud is to be 45 entered in the socket, the annular jaw 9 will

be forced outwardly so that it can pass over the stud 4.

Similarly, the interior shoulder of the groove 7' is preferably rounded so that, as the stud is entered in the socket, the passage of the groove 7' of the stud past the jaw 9 will not prevent the full entrance of the stud in the socket. When the stud is completely entered in the socket, as shown, 60 the jaw 9 rests in the groove 6' and the second resilient jaw element 10 is entered in the groove 7' so that, if pressure is exerted outwardly on the curtain in any non-axial direction the resilient jaw element 10 will 65 firmly press against the shoulder provided by the groove 7' and head 13, thus preventing accidental withdrawal of the stud from the socket. When, on the other hand, the stud is directly withdrawn from the socket, 70 the head 13 can pass through the resilient jaw 10 by expansion of the ring 10. If the stud is for any reason accidentally partially withdrawn from the socket, the spring jaw 9 will engage the groove 7', thus providing 75 one form of double locking means, or means for yieldingly holding the stud and socket in a plurality of determined positions.

The preferred form of stud and socket provides plural independent jaw means engaging the stud, which not only increase the strength of the resilient attachment of the stud to the socket, but also provide co-acting resilient fulcrum elements opposing extended withdrawal of the stud from the 80 socket by force exerted in any non-axial direction.

While I have shown and described a preferred form of one embodiment of my invention, it will be understood that changes 85 involving omission, substitution, alteration and reversal of parts, and even changes in the mode of operation, may be made without departing from the scope of my invention, which is best defined in the following 90 claims.

Claims:

1. A separable fastener comprising, in combination, a stud providing two grooves spaced longitudinally thereof, and a tubular 10 socket adapted to receive said stud and having interiorly thereof two grooves spaced to

correspond to the grooves of the stud, two of said grooves retaining annular spring portions for engagement with oppositely disposed grooves.

5 2. A separable fastener comprising, in combination, a stud providing two grooves spaced longitudinally thereof, and a tubular socket adapted to receive said stud and hav-

ing interiorly thereof two grooves spaced to correspond to the grooves of the stud, two of said grooves in said socket retaining annular spring portions for engagement with oppositely disposed grooves in said stud.

In testimony whereof, I have signed my name to this specification.

MOSES F. CARR.
